CLAIM

The ornamental design for a toolbox, as shown and described.

DESCRIPTION

FIG. 1 is a perspective view of a toolbox according to a first embodiment of the invention.

FIG. 2 is a front elevational view of a toolbox according to a first embodiment of the invention.

FIG. 3 is a rear elevational view of a toolbox according to a first embodiment of the invention.

FIG. 4 is a left side elevational view of a toolbox according to a first embodiment of the invention; the opposite side being a mirror image thereof.

FIG. 5 is a top plan view of a toolbox according to a first embodiment of the invention.

FIG. 6 is a bottom plan view of a toolbox according to a first embodiment of the invention.

FIG. 7 is a perspective view of a toolbox according to a second embodiment of the invention.

FIG. 8 is a rear view of a perspective view of a toolbox according to a second embodiment of the invention when folded.

FIG. 9 is a front elevational view of a toolbox according to a second embodiment of the invention.

FIG. 10 is a rear elevational view of a toolbox according to a second embodiment of the invention.

FIG. 11 is a left side elevational view of a toolbox according to a second embodiment of the invention; the opposite side being a mirror image thereof.

FIG. 12 is a top plan view of a toolbox according to a second embodiment of the invention; and,

FIG. 13 is a bottom plan view of a toolbox according to a second embodiment of the invention.
